UNITED STATES PATENT OFFICE.

WILLIAM H. ARMSTRONG, OF PLAINFIELD, NEW JERSEY, ASSIGNEE TO INGERSOLL-BAND COMPANY, OF JERSEY CITY, NEW JERSEY, A CORPORATION OF NEW JERSEY.

TOOL-RETAINER.

1,188,383.

Specification of Letters Patent. Patented June 27, 1916.

Application filed October 29, 1913. Serial No. 797,980.

To all whom it may concern:

Be it known that I, WILLIAM H. ARMSTRONG, a citizen of the United States, residing at Plainfield, in the county of Union 5 and State of New Jersey, have invented a certain new and useful Improvement in Tool-Retainers, of which the following is a specification.

This invention relates to tool retainers 10 for percussive tools and more particularly to such a retainer for use in holding in the rivet set in a riveting hammer.

The object of the invention is to provide such a retainer which will be of comparatively simple construction and yet capable of bearing the great stress which these retainers are often subjected to, for such a period of time that any chance of accident will be practically eliminated.

With this object in view, I have devised 20 a tool retainer, practical embodiments of which are shown in the accompanying drawings in which:

Figure 1 shows a longitudinal section 25 through the front end of a riveting hammer cylinder showing the rivet retainer in position; Fig. 2 is a transverse section taken on the line II—II of Fig. 1; Fig. 3 is a front elevation of a tool and rivet retainer with the head of the rivet set cut away; Fig. 4 is a top view of the retainer; Fig. 5 is a longitudinal section through a modified form of retainer and Fig. 6 is an end elevation of the retainer shown in Fig. 5.

In the drawings is shown the front end of 35 a tool cylinder 1, the tool being of ordinary construction and provided with a rivet set 2 of ordinary construction which comprises a shank 3 sliding in the forward end of this cylinder, at the forward end of which is a flange 4 which serves to limit the backward movement of the rivet set and also to provide a holding surface for the retainer.

The retainer proper consists of a sleeve 45 5 whose interior diameter, for a greater part of its length, is greater than the outer diameter of the tool barrel and which is provided at its rear end with an inturned flange portion 6 which slides on the surface 50 of the tool cylinder. The forward part of the sleeve slides on an annular flange or projection 7 which is threaded or otherwise secured, to the extreme end of the tool barrel. Surrounding the tool barrel inside of 55 the sleeve 5 is a spring 8 which is shown in

Fig. 1 to be of less length than the distance between the flange 6 and the flange 7 when the sleeve 5 is in its rearmost position although it may be of greater length.

In the sleeve 5, outside of the spring 8, 60 are pivotally mounted, one or more (here shown as two) tool retaining dogs 9. In Figs. 1 to 4 these dogs are shown as having rectangular rear portions 10 and necks 11 which fit into inwardly cut slots 12 in the forward part of the sleeve 5, the shoulders 13 of the rear portions 10 preventing forward movement of the dogs in the sleeve and providing pivot points for them. The forward parts of the dogs 9 widen out and 65 turn inwardly forming jaws 14 for grasping the rivet set, contact of the flange 4 with these jaws preventing anything more than limited forward movement of the rivet set. The inner faces of the rear portions 10 of the dogs 9 are provided with projecting surfaces 15 which are adapted to ride up on the outer surface of the spring 8 when the dogs 9 and the sleeve 5 move forward under the impact of the flange 4 of the rivet set 70 against the jaws 14. In this way the jaws 14 will be forced into close contact with the neck of the rivet set preventing it from flying out of the tool barrel.

To keep the jaws always in operative position straight steel springs 16 are provided, the centers of which rest on shoulders on the flange 6 and the ends of which press against the inner surfaces of projections 17 on the extreme rear ends of the dogs 9. 85

The operation of this device will be evident from the above description. When the riveter is in ordinary operation, the sleeve does not move as the jaws 14 are not in contact with the flange 4 of the rivet set. If, however, the motive fluid of the tool is turned on when the rivet set is not in contact with the work, the rivet set will move forward and the flange 4 coming in contact with the jaws 14 will move them forward, at the same time moving the sleeve 5 with them. As these parts move forward the projecting surfaces 15 on the dogs will ride up on to the spring 8 forcing the jaws 14 into tight contact with the neck of the rivet set thus preventing the flange 4 from passing out between the jaws. 95

When the flange 6 comes into contact with the spring 8 the forward movement of the dogs and sleeve will be cushioned and 100 105 110

the stress of the hammer blow of the tool piston taken up. When it is desired to remove the rivet set the sleeve and dogs are moved to their rearmost positions and the rear ends of the dogs pushed inwardly against the springs 16 so that the rivet set can be removed.

In Figs. 5 and 6, a modified form is shown in which the dogs 9 are pivoted on pins 18 secured in lugs 19 on the sleeve 5. In this form the dogs are not in contact with the spring 8 but are retained in operative position by heavy flat springs 20 which press outwardly against their rear ends.

15 Although the retainer is here shown in connection with a riveting tool, it is adapted for use with any form of percussive tool or drill where the tool or drill is loosely held in the cylinder and it is to be understood that the present showing and description discloses only certain specified modifications of my invention and other forms and modifications are included in the spirit and scope of the invention as expressed in the claims.

What I claim is:

1. In a tool retainer for percussive tools, a tool cylinder, a sleeve slidably mounted on the forward end of the tool cylinder, one or more dogs having tool grasping jaws pivotally mounted in said sleeve, means to force said jaws into contact with the tool, and resilient means for opposing forward motion of said sleeve.

35 2. In a tool retainer for percussive tools, a tool cylinder, a sleeve having an inturned flange, slidably mounted on the forward end of the tool cylinder, a spring inside of said sleeve, a projection on the cylinder end to hold said spring from forward movement, one or more dogs having jaws adapted to engage the tool pivotally mounted in said sleeve, and means to hold said jaws in contact with said tool.

3. In a tool retainer for percussive tools, a tool cylinder, a sleeve having an inturned flange, said sleeve being slidably mounted on the forward end of the tool cylinder, a projection on the extreme forward end of said cylinder, a spring inside said sleeve, between said flange and said projection, one or more dogs having jaws adapted to engage the tool pivotally mounted on said sleeve and resilient means to force the jaws into contact with said tool.

4. In a tool retainer for percussive tools, a tool cylinder, a sleeve having an inturned portion, slidably mounted on the forward end of the tool cylinder, an annular projection on the forward end of the tool cylinder, a spring inside of said sleeve between said inturned portion and said projection and one or more dogs pivotally mounted in said sleeve, said dogs having tool grasping jaws, and rear portions adapted to ride on said spring and force said jaws inwardly during forward movement of said sleeve.

5. In a tool retainer for percussive tools, a tool cylinder, a projection on the forward end of the tool cylinder, a sleeve slidably mounted on the forward end of the tool cylinder and having an inturned portion, a short spring inside of said sleeve between said inturned portion and said projection, one or more dogs pivotally mounted in said sleeve, said dogs having tool grasping jaws and rear portions out of contact with said spring when the sleeve is in its rearmost position, and adapted to ride up on said spring during forward motion of said sleeve, and resilient means to hold said jaws at all times in contact with the tool.

In testimony whereof, I have hereunto set my hand.

WILLIAM H. ARMSTRONG.
